UNITED STATES PATENT OFFICE.

JOSEPH NOVIN, OF NEW YORK, N. Y., ASSIGNOR TO THE CENTRE LIGHTING FIXTURE MFG. CO., A PARTNERSHIP CONSISTING OF SAID NOVIN, AND SAMUEL RIBAK, DOING BUSINESS AT NEW YORK, N. Y.

DESIGN FOR A LIGHTING FIXTURE.

Application filed December 23, 1924. Serial No. 11,771. Term of patent 3½ years.

To all whom it may concern:

Be it known that I, JOSEPH NOVIN, a citizen of the United States, and a resident of the city of New York, county of Bronx, and State of New York, have invented a new, original, and ornamental Design for Lighting Fixtures, of which the following is a specification, reference being had to the accompanying drawing, forming a part hereof.

In the drawings:

Figure 1 is a front elevational view of the lighting fixture;

Figure 2 is a top plan view of the lighting fixture; and

Figure 3 is a side elevation of the same.

The fixture is characterized by a back plate *a* adapted for mounting the fixture on a wall, a vase *b* carried in front of the back plate, and two candle cups *d* and *d'* supported on arms *c* and *c'* extending from underneath the vase.

I claim:

The ornamental design for a lighting fixture substantially as shown and described.

JOSEPH NOVIN.
